ROTARY ROD WEEDER

Filed Aug. 4, 1927

2 Sheets-Sheet 1

<img alt="A detailed technical line drawing of a mechanical device, likely a wheelbarrow or cart, with various numbered components. The drawing includes a large wheel at the top, a central frame with a seat, and two smaller wheels at the bottom. Numerous numbered parts are shown, such as 1 through 5, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 2061, 2062, 2063, 2064, 2065, 2066, 2067, 2068, 2069, 2069, 2070, 2071, 2072, 2073, 2074, 2075, 2076, ROTARY ROD WEEDER

Filed Aug. 4, 1927

2 Sheets-Sheet 2

UNITED STATES PATENT OFFICE.

RALEIGH M. LARGENT, OF WALLA WALLA, AND LOUIS C. VAN PATTEN, OF CHENEY,
WASHINGTON, ASSIGNEES TO CHENEY WEEDEER COMPANY, OF CHENEY, WASH-
INGTON, A CORPORATION OF WASHINGTON.

ROTARY-ROD WEEDEER.

Application filed August 4, 1927. Serial No. 210,626.

- Our invention relates in general to the art of agriculture and it specifically relates to that branch of the art having to do with the extermination of weeds.
- 5 The invention has for an object to provide a weeder of a generally well known type (rotary rod) with means to facilitate the entry of the rod into the ground, the maintaining of the rod in proper position beneath the surface of the ground and the provision of means by which the rod may be adjusted to various depths with ease and dispatch.
- 10 Further, it is an object to provide such a weeder with a peculiar draft appliance by the use of which a material increase in the downward component of force tending to sink the rotary rod beneath the surface is obtained without the necessity of adding weight to the machine.
- 15 Again it is an object to provide a weeder of the type mentioned in which provision is made whereby by simply manipulating the lever that adjusts the depth of the rod, the line of draft can be so located with the rod out of the ground that in drawing the machine over the ground to transport it from field to field the draft pull will tend to exert an upward component of force or lift to the front and heavier part of the machine, thereby preventing the driving and supporting wheels from digging in or tending to sink into soft ground, and consequently facilitating the transportation of the machine from place to place.
- 20 Further it is an object of said invention to provide a weeder, the rotary rod of which is supported to the rear of the axis of the driving and supporting wheels and the point of draft application is located to the rear of the rotary rod and below the axis of the driving and supporting wheels.
- 25 Still further it is an object of the invention to provide a weeder comprising a main frame supported by the driving and supporting wheels to which is secured a tiller frame supported at one end by a tiller wheel or tiller wheels and at the other end is pivotally connected to the main frame at the rear of the traction and supporting wheel's axis. The tiller frame and the main frame also have a lever and link connection at a place remote from the pivotal connection whereby the main frame may be inclined with respect to the tiller frame, and means are associated
- 30 and combined with the aforesaid structure for applying the traction pull to the same at a point in the rear of the driving and supporting wheels' axis for the purpose of increasing the force tending to cause the rod to sink into the ground and maintain it in proper location beneath the surface.
- 35 Other objects will in part be obvious and in part be pointed out hereinafter.
- To the attainment of the aforesaid objects and ends, our invention consists in the novel details of construction, and in the combination, connection and arrangement of parts hereinafter more fully described and then pointed out in the claims.
- 40 In the accompanying drawings showing an illustrative embodiment of the invention, Figure 1 is a perspective view of a preferred embodiment of the invention.
- 45 Figure 2 is a plan view of the same.
- 50 Figure 3 is an end elevation, the parts being adjusted with the rotary rod at approximately its maximum depth in the ground under working conditions.
- 55 Figure 4 is a diagrammatic elevation showing the rod elevated from the ground.
- 60 In the drawings, in which like numerals of reference indicate like parts in all the figures, 1 represents the front bar of the main frame, which frame is composed of front and rear bars 1 and 2 respectively, and the longitudinal bars 3 suitably secured to the front and rear bars at proper intervals.
- 65 Mounted in suitable bearings on the main frame is the supporting wheel axle 4 that carries the supporting wheel 5 at one end of the frame. Mounted in other suitable bearings on the main frame is the driving wheel axle 6 which carries the driving wheel 7.
- 70 It will be observed from Figure 2 that the rear bar 2 of the main frame is extended at one end and to this extension is secured a pair of supplemental longitudinal bars 8 spaced apart a suitable distance to permit operation of the driving chain and sprocket. On the bars 8 there are brackets 9 for supporting the shaft of the idler sprocket 10. There are also brackets 11 for supporting the idler sprocket 12. Beneath the extension bars 8—8 in the rear are brackets 13 for the countershaft 17, the latter being driven from the driving wheel 7 through the medium of the main drive sprocket 15, drive chains 16 and sprockets 17, the drive chain 16, of course,

passing over the idler sprockets 10 and 12 respectively.

Connected with the shaft 17 is a tumbling rod 18 that also connects to the rotary rod 19, the connections between the tumbling rod 18, the rotary rod 19 and countershaft 17 being through universal joints 20 and 21.

Secured to the upper portion of the standards 47, which carry the bearing shoes 45 10 and the rotary rod 19, are pairs of arms 22. These arms extend downwardly and rearwardly in pairs, each pair having their ends connected to a bolt 23 which also serves as a pivotal connection for the draft rod 24 secured thereto. It should be understood that there is a draft rod secured to each pair of extension bars 22 and these draft rods pass forwardly beneath the main frame of the machine and between guides 25 that are provided 15 with pins or bolts 26 to prevent the rod 24 from dropping too low, the pins or bolts 26 passing through one of a series of apertures in the guides 25. Each draft rod 24 has an eye or other suitable means 27 by which the 25 draft links 28 may be attached.

Pivotedly secured at 44 to suitable brackets secured beneath and to the rear cross bar 2 are bars 29 which extend rearwardly and, when a single tiller wheel is used converge to 30 their rear ends where they are fastened to the caster wheel support 34 which is in turn fastened to the transverse short angle iron or bar 30 to which is also secured short longitudinal angle irons 31 to support the bearings 32 for 35 the adjustment shaft 33. 36 is the caster or tiller wheel whose king bolt 35 is mounted in the caster wheel support 34 in the usual way.

37 is a seat post which carries a seat 38 on which the operator may rest.

40 Suitably secured rigidly with respect to the tiller frame is an arcuate rack 39 to cooperate with the latch of the adjusting lever 40 to hold the shaft 33 in any of a series of positions. Secured to the shaft 33 is a pair of 45 adjusting arms 41 which are pivoted at 43 to the connecting links 42, the latter being pivoted at 23 to the respective pair of extension bars 22. 44 designates the pivotal connection of the bars 29 to the brackets of the 50 rear bar 2.

The gooseneck standards 47 carry the usual rod bearing shoes 45.

The arrows marked 46 in the drawings indicate the direction of pulling power when 55 draft is applied to the links 28.

Assume that the parts are in the position diagrammatically illustrated in Figure 4 and draft is being applied in the direction of the arrow 46. Since there are but three points 60 of contact with the ground, namely the contacts of the wheels 5, 7 and 36, it will be obvious from Figure 4 that any pull in the direction of the arrow 46 will have a tendency to exert a slight lift on the forward end of 65 the vehicle which will facilitate its passage

over the ground since the draft rod 24 engages the front bar 1 of the frame.

Now assume that it is desired to have the rod enter the ground, the operator manipulates the lever 40 by releasing the latch to 70 bring the shoes 45 into contact with the ground. The instant this occurs there will be a change as it were in the fulcrum or pivotal point of the machine. This being now shifted to the points of the shoes results in the entire weight of the machine being made available for forcing the shoes with the rod into the ground. Since the point of draft 23 is below the axis of the wheels 5 and 7 when the rotary rod is in engagement with the 75 ground and as the points of the draft 23 are to the rear of the rotary rod, it is obvious that a downward component of force is present at 23 and a consequent upward component of force at the axis 4-6, thereby applying the 80 draft power with increased leverage to the 85 shoes 45.

Experiments made with this machine have demonstrated that by the application of the draft through the rod 3 at a place located beneath the axis 4-6 and to the rear of the rotary rod, the effect is the same as if several hundred pounds added weight were supplied to the machine. Thus it will be observed by this arrangement we have provided for a considerable increase in the component of force necessary to sink the rod beneath the ground and in consequence we have produced a machine that can be worked in hard ground with greater facility than other machines now 90 known. Attention is also called to the fact that the point of draft being located behind and below the axles not only gives a splendid leverage for penetration in the ground but as the rod goes deeper in the ground the point 95 of draft behind and below the axle comes closer to the ground. The leverage increases further which is a distinct help as the resistance increases because of the depth of the rod in the ground. Furthermore, by constructing the machine as shown and described we find that the framing of the machine can be built much lighter than the usual practice since the strains thereon are correspondingly reduced. We have found from actual practice that we can use $\frac{1}{16}$ inch angle irons in 100 building the framing whereas ordinarily in weeder 105 of this general type $\frac{3}{8}$ inch angle irons are required. 110

From the foregoing description taken in 115 connection with the accompanying drawings, it is thought the construction, operation and advantages of our invention will be clear to those skilled in the art.

It is quite obvious that changes in the 120 details of construction and in the general design of the machine can be made without departing from the principle of the invention or the scope of the appended claims.

While the present invention was devised 125

particularly with respect to rotary rod weeders it is quite obvious that it may be used in connection with other kinds of agricultural machines as, for instance, stationary rod 5 weeder, blade weeder and other wheeled cultivators employing ground-working elements which are adapted to penetrate the surface of the ground and such adaptations can be made without departing from the spirit of 10 the present invention.

What we claim is:

1. In a rotary rod weeder wherein is provided a main frame, a rotary rod, a driving wheel, a supporting wheel and axles for said 15 wheels journalled in bearings on said frame; the combination with the aforesaid parts, of a draft appliance underlying the main frame and connected therewith at a place to the rear of the rotary rod and in a plane below 20 said axles.

2. In a rotary rod weeder wherein is provided a main frame, a rotary rod a driving wheel, a supporting wheel, axles for said 25 wheels journalled in bearings on said frame; the combination with the aforesaid parts, of a draft appliance underlying the main frame and connected therewith at a place to the rear of the rotary rod and in a plane below said axles; a tiller frame pivoted to said main 30 frame; a wheel supporting the outer end of said tiller frame; and a lever and link connection between said frames.

3. In a rotary rod weeder wherein is provided a main frame, a rotary rod, a driving 35 wheel, a supporting wheel, axles for said wheels journalled in bearings on said frame; the combination with the aforesaid parts, of a draft appliance underlying the main frame and connected therewith at a place to the 40 rear of the rotary rod and in a plane below said axles; a tiller frame pivoted to said main frame and extending rearwardly beyond the place where said draft appliance is connected; a wheel supporting the outer end of said 45 tiller frame; and a lever and link connection between said frames.

4. In rotary rod weeder, a main frame, standards carried thereby, a rotary rod journalled in bearings in said standards, driving 50 and supporting wheels and axles journalled in bearings on said main frame, power transmitting connections between said driving wheel and said rotary rod, combined with means to apply draft force to the aforesaid 55 structure at a place to the rear of said rotary rod and to the rear of and below the axes of said driving and supporting wheels.

5. In rotary rod weeder, a main frame, standards carried thereby, a rotary rod journalled in bearings in said standards, driving 60 and supporting wheels and axles journalled in bearings on said main frame, power transmitting connections between said driving wheel and said rotary rod, combined with

means to apply draft force to the aforesaid 65 structure at a place to the rear of said rotary rod and to the rear of and below the axes of said driving and supporting wheels, said last named means comprising extension bars extending rearwardly and downwardly of the 70 main frame, and a draft rod pivoted to said extension bars and underlying said main frame, to the forward end of which draft rod the draft power is applied.

6. In rotary rod weeder, a main frame, 75 standards carried thereby, a rotary rod journalled in bearings in said standards, driving and supporting wheels and axles journalled in bearings on said main frame, power transmitting connections between said driving 80 wheel and said rotary rod, combined with means to apply draft force to the aforesaid structure at a place to the rear of said rotary rod and to the rear of and below the axes of said driving and supporting wheels, said last 85 named means comprising extension bars extending rearwardly of the main frame, guides at the front of said main frame, a draft rod pivoted to said extension bars and underlying said main frame, said draft rod adapted to have the draft power connected to the forward end thereof, said draft rod passing between said guides for the purpose specified.

7. In rotary rod weeder, a main frame, 90 standards carried thereby, a rotary rod journalled in bearings in said standards, driving and supporting wheels and axles journalled in bearings on said main frame, power transmitting connections between said driving 95 wheel and said rotary rod, combined with means to apply draft force to the aforesaid structure at a place to the rear of said rotary rod and to the rear of and below the axes of said driving and supporting wheels, said last 100 named means comprising extension bars extending rearwardly and downwardly on the main frame, and a draft rod pivoted to said extension bars and underlying said main frame, to the forward end of which draft rod the draft power is applied, a tiller frame 105 composed of bars hinged at their front to the rear of said main frame and extending rearwardly beyond said extension bars, a cross bar secured to said tiller frame bars, a caster wheel for supporting the free ends of said tiller frame bars, a shaft journalled in bearings sustained by said cross bar, an operating lever secured to said shaft, a rack and pawl device to hold said lever, and a lever and link connection between said shaft and said extension bars of the main frame for the purpose specified.

8. In rotary rod weeder having frames supported on wheels, beneath which frames and to the rear of the axes of the wheels a rotary rod is held; means for facilitating the sinking of the rod into the ground, said means comprising a draft appliance connected to 115 120 125

act at a point below the axes of said wheels in a plane above said rotary rod and to the rear of both said axes and rods.

9. In rotary rod weeders having frames supported on wheels, beneath which frames and to the rear of the axes of the wheels a rotary rod is held; means for facilitating the sinking of the rod into the ground, said means comprising a draft appliance connected to act at a point below the axes of said wheels in a plane above said rotary rod and to the rear of both said axes and rods; combined with means for holding the rod to a predetermined depth below the ground surface.

10. In agricultural machines of the type wherein is provided a frame mounted on wheels and at least one ground working element carried by said frame; the combination with the aforesaid parts of a draft appliance underlying the frame and connected therewith at a place to the rear of the ground working element and in a plane below the axes of the wheels.

11. In agricultural machines, a main frame, standards carried thereby, ground working implements mounted on said standards and adapted to penetrate the ground, wheels and axles for supporting said frame above the ground; combined with means to apply draft force to the aforesaid structure at a place to the rear of said ground working implements and to the rear of and below said axles.

12. In agricultural machines, a main frame, standards carried thereby, ground working implements mounted on said standards and adapted to penetrate the ground, wheels and axles for supporting said frame above the ground; combined with means to apply draft force to the aforesaid structure at a place to the rear of said ground working implements and to the rear of and below said axles, said last named means comprising extension bars extending rearwardly and downwardly of the frame, and a draft rod pivoted to said extension bars and underlying said main frame, to the forward end of which draft rod the draft power is applied.

13. In agricultural machines, a main frame, standards carried thereby, ground working implements mounted on said standards and adapted to penetrate the ground, wheels and axles for supporting said frame above the ground; combined with means to apply draft force to the aforesaid structure at a place to the rear of said ground working implements and to the rear of and below said axles, said last named means comprising extension bars extending rearwardly of the main frame, guides at the front of said main frame, a draft rod pivoted to said extension bars and underlying said main frame, said draft rod adapted to have the draft bar connected to the forward end thereof, said draft rod passing between said guides for the purposes specified.

14. In agricultural machines having frames

supported on wheels, beneath which said frames and to the rear of the axles of the wheels a ground working implement is held; means for facilitating the sinking of the implement into the ground, said means comprising a draft appliance connected to act at a point below the axes of the wheels in a plane above said ground working implement and to the rear of both said axles and implement.

15. In agricultural machines having frames supported on wheels, beneath which said frames and to the rear of the axles of the wheels a ground working implement is held; means for facilitating the sinking of the implement into the ground, said means comprising a draft appliance connected to act at a point below the axes of the wheels in a plane above said ground working implement and to the rear of both said axles and implement, combined with means for holding said implement to a predetermined depth below the ground surface.

16. In agricultural machines of the type wherein is provided a frame mounted on wheels and at least one ground working element carried by said frame; the combination with the aforesaid parts of a draft appliance underlying the frame and connected therewith only at a place in a plane below the axes of the wheels whereby the draft force will continuously tend to assist the working element to enter and remain beneath the surface of the ground.

17. In agricultural machines, a main frame, standards carried thereby, ground working implements mounted on said standards and adapted to penetrate the ground, wheels and axles for supporting said frame above the ground; combined with means to apply draft force to the aforesaid structure only at a place to the rear of and below said axles whereby the draft force will continuously tend to assist the working element to enter and remain beneath the surface of the ground.

18. In agricultural machines, a main frame, standards carried thereby, ground working implements mounted on said standards and adapted to penetrate the ground, wheels and axles for supporting said frame above the ground; combined with means to apply draft force to the aforesaid structure at a place to the rear of and below said axles, said last named means comprising extension bars extending rearwardly and downwardly of the frame, and a draft rod pivoted to said extension bars and underlying said main frame, to the forward end of which draft rod the draft power is applied said draft rod being free of the frame whereby it may rise and fall beneath the frame with motion on its pivot.

19. In agricultural machines having frames supported on wheels, beneath which said frames and to the rear of the axles of the wheels a ground working implement is held;

means for facilitating the sinking of the implement into the ground, said means comprising a draft appliance connected to act at a point below the axes of the wheels in a plane above said ground working implement and to the rear of said implement.

20. In agricultural machines having frames supported on wheels, beneath which said frames and to the rear of the axes of the 10 wheels a ground working implement is held; means for facilitating the sinking of the implement into the ground, said means comprising a draft appliance connected to act at a point below the axes of the wheels in a plane 15 above said ground working implement and to the rear of said implement, combined with means for holding said implements to a predetermined depth below the ground surface.

21. In agricultural machines of the type 20 wherein is provided a frame mounted on wheels and at least one ground working element carried by said frame; the combination with the aforesaid parts, of a draft appliance underlying the frame and pivotally connected therewith at a single place located in a plane 25 below the axes of the wheels and behind the axes of the wheels.

22. In agricultural machines of the type wherein is provided a frame mounted on 30 wheels and at least one ground working element carried by said frame; the combination with the aforesaid parts, of a draft appliance underlying the frame and pivotally connected therewith in a plane below the axes of the 35 wheels and behind the axes of the wheels, guides at the front of the frame for said draft appliance permitting up and down move-

ment of the front of said draft appliance pivotally on its pivotal axis.

23. In agricultural machines of the type 40 wherein is provided a frame mounted on wheels and at least one ground working element carried by said frame; the combination with the aforesaid parts, of a draft appliance underlying the frame and pivotally connected therewith in a plane below the axes of the 45 wheels and behind the axes of the wheels, guides at the front of the frame for said draft appliance permitting up and down movement of said draft appliance pivotally on its pivotal axis, and means for tilting said frame to raise and lower said working element with respect to the ground.

24. In agricultural machines, a main 50 frame, standards carried thereby, ground working implements mounted on said standards and adapted to penetrate the ground, wheels and axles for supporting said frame above the ground; combined with means to apply draft force to the aforesaid structure 55 at a place to the rear of said ground working implements and to the rear of and below said axles, said last named means comprising extension bars extending rearwardly of the main frame, guides at the front of said main 60 frame, a draft rod connected to said extension bars and underlying said main frame, said draft rod adapted to have the draft bar connected to the forward end thereof, said draft rod passing between said guides for the purposes specified.
